UNITED STATES PATENT OFFICE

98,139

DESIGN FOR A WATCH BRACELET

Marvin J. Bruner, New York, N. Y.

Application November 26, 1935, Serial No. 59,768

Term of patent 3½ years

To all whom it may concern:

Be it known that I, Marvin J. Bruner, a citizen of the United States, residing in New York city, in the county of New York and State of New York, have invented a new, original, and ornamental Design for a Watch Bracelet, of which the following is a specification, reference being had to the accompanying drawing, forming part thereof.

Fig. 1 is a plan view of a watch bracelet showing my new design.

Fig. 2 is an edge view of the same.

I claim:

The ornamental design for a watch bracelet as shown.

MARVIN J. BRUNER.
